UNITED STATES PATENT OFFICE.

JACOB M. SHOLL, OF MILWAUKEE, WISCONSIN.

CRUSHING-MACHINE.

1,038,794.

Specification of Letters Patent. Patented Sept. 17, 1912.

Application filed February 15, 1908. Serial No. 416,021.

To all whom it may concern:

Be it known that I, JACOB M. SHOLL, a citizen of the United States, residing at Milwaukee, in the county of Milwaukee and 5 State of Wisconsin, have invented certain new and useful Improvements in Crushing-Machines, of which the following is a full, clear, and exact specification.

My invention relates to crushing machines 10 having gyratory shafts and crusher heads carried thereon, and particularly to that form of the same in which the upper end of the gyratory shaft is suspended in the hub of a top support plate or spider and the 15 crushing head is carried in a crushing chamber, the lower end of the shaft being caused to move in a small circle, thus giving the shaft a gyratory movement. When stones or ore is thrown into the crushing chambers 20 of such machines, it is crushed as the head advances toward the wall of the crushing chamber and is allowed to fall as the head recedes until it is reduced sufficiently in size 25 to fall through the opening at the bottom of the chamber into a discharge hopper or chute.

The primary object of the invention is to provide an improved form of crusher of the 30 class described which shall be simple in construction and efficient in operation and in which the height of the machine may be reduced, thereby facilitating feeding and at the same time reducing the weight, the initial cost of construction, the cost of transportation, and the cost of the foundation or 35 supporting structure.

A further object of the invention is to provide in a crusher of the class described improved means by which the various running or exposed parts are protected from 40 wear and from dust.

A further object is to provide an improved form of adjustable upper bearing for supporting the suspended main gyratory shaft.

A further object is to provide an improved construction of top shell or crushing chamber and spider for supporting the gyratory main shaft, whereby these parts may be formed integral with each other dispensing 45 with the labor and expense necessary to machine and assemble them.

A still further object of the invention is to provide an improved form of hopper whereby the spider arms which support the main 50 gyratory shaft may be protected from wear

due to the passing of material to be crushed through the hopper, and to facilitate feeding.

To the attainment of these ends and in order to accomplish other new and useful 60 results the invention consists in the features of novelty described in the specification, pointed out more specifically in the appended claims and shown in the accompanying drawings.

In the said drawings Figure 1 is a vertical section, partly in elevation of the complete machine. Fig. 2 is an elevation of the complete machine looking into the discharge spout. In this view a portion of the feed 70 hopper is shown in section to illustrate the construction thereof. Fig. 3 is a plan section taken on line 3—3, Fig. 1, and shows the relation of the various parts which impart the gyratory motion to the main shaft. 75 In this view collar 27^c is removed. Fig. 4 is a detail view in horizontal section partly in elevation of a modified form of mechanism which may be adapted for imparting rotary movement to the eccentric ring instead of the rim-pulley drive shown in Fig.

1. Fig. 5 is a detail view in sectional elevation of the clamping adjusting nut on the upper end of the main gyratory shaft, on line 5—5 of Fig. 6. Fig. 6 is a plan view 85 partly in section of the parts shown in Fig. 5. Fig. 7 is an enlarged detail section illustrating the form of thread on the adjusting nut and the upper end of the main gyratory shaft. Fig. 8 is a broken sectional elevation 90 illustrating a modified form of the machine shown in Fig. 1 in which the spider which is used in suspending the main gyratory shaft is constructed separately from the upper shell or crushing chamber. Fig. 9 is a broken 95 view in elevation showing the upper part of the machine constructed according to the modified form shown in Fig. 8, with the spider supporting the gyratory shaft detachably connected to the upper shell or crushing chamber. Fig. 10 is a plan view in section and Fig. 11 a view in elevation of one section of the preferred form of roller bearing cage used to secure anti-friction 100 bearings for the eccentric driving ring. 105 Figs. 12 and 13 are detail sectional views taken through diametrically opposite sides of the eccentric driving ring and the rim-pulley secured thereto for driving the same, the view in Fig. 12 being taken through the 110

ring on the side having a maximum thickness, while the section in Fig. 13 is taken on the side having the minimum thickness. The adjacent roller bearings are shown in each view in elevation. Fig. 14 is a detail plan view of a portion of the rim pulley secured to the eccentric ring as the parts appear in vertical section in Fig. 13. Fig. 15 is a broken vertical sectional view partly in elevation illustrating a modified form of the discharge hopper and spout in which said hopper and spout are carried by the spider which imparts the gyratory motion to the main shaft.

15 The top shell or crushing chamber of the machine is indicated by the reference character 10. In the interior of this chamber is the usual form of crushing head 11 which is sleeved on main gyratory shaft 12. This 20 shaft 12 may be supported in its gyratory movement in any desired or suitable manner as is common in this class of machines. It is preferred, however, that it be suspended from its upper support and to furnish this upper 25 bearing and to take the side pressure the spider 10^a is provided, which is preferably integral with the upper shell or crushing chamber 10, although in some of the larger sizes of machines it may be found desirable 30 to construct this spider or support separate from crushing chamber 10, as illustrated in Figs. 8 and 9 in which the crushing chamber is indicated by the reference character 13, and the spider by 14. In the form of these 35 parts illustrated in Figs. 8 and 9, it is necessary that each of the parts be machined in order that they may fit together properly and in addition to the labor involved, retaining bolts 15 must be provided, all of 40 which expense is avoided by the construction shown in Fig. 1. The crushing head 11 may be secured to main gyratory shaft 12 in any desired manner. It is preferred, however, that the shaft be formed with a 45 uniformly increasing diameter from the part designed to receive the upper end of the head to the lower end thereof and the interior of the head be formed to correspond with the conical form of the shaft 50 in order that any tendency of the head to turn on the shaft combined with its weight will cause it to settle until all looseness is taken up. If desired, the head may be prevented from turning on the shaft by a 55 feather or spline inserted between the parts in the usual manner and the head may be held against any tendency to rise on the shaft by means of the threaded collars 16 and 17. The upper end of shaft 12 is pref- 60 erably cylindrical in form and extends through a bearing formed in the hub of the spider 10^a. 18 is a bushing inserted in this bearing. In order to permit the gyratory movement of shaft 12, the bearing formed 65 in the bushing 18 is of a gradually increas-

ing diameter from the bottom to the top thereof, so that the bearing forms a snug fit around the shaft at the bottom, thus determining the axis of the gyratory movement of the shaft. In Fig. 1 the shaft 12 is 70 shown at the limit of its movement or throw toward the left as the observer faces the machine.

19 is the suspension nut which is threaded to correspond to the threaded upper portion of shaft 12. The lower portion of this nut which is preferably thicker than the upper portion in order to form a suitable bearing rests upon a wearing ring 20, thus carrying the weight of the shaft and the crushing head. The construction of suspension nut 19 is shown in detail in Figs. 5, 6 and 7, from which it will be seen that the upper portion of this nut has slotted openings 21 and that it is provided with a tapered sleeve 22 which may be driven down on it forcing the threads together in order to lock it in its adjusted position. As a detail of construction this nut is preferably formed with a recess or groove 19^a on its interior and is threaded only above such groove or recess. This construction permits the shaft 12 to be raised and lowered by adjusting this suspension nut which enables the crushing head 11 to be adjusted in relation to the crushing chamber and the concaves 23, which form the interior lining thereof. Tap bolts 24 may be used for securing sleeve 22 after it is driven or drawn to its locking position. These same bolts may be used to screw into tapped holes 22^a when it is desired to loosen the sleeve from the suspension nut, the lower ends of these bolts bearing against the upper surface of the suspension nut, there being no holes formed therein to correspond with holes 22^a in the sleeve. The form of thread known as the acme thread, which is illustrated in Fig. 7, is preferred for use on the suspension nut and shaft but it will be apparent that any thread with tapering sides as for example U. S. standard V thread which will permit of locking the nut on the shaft in the manner described may be used. There is a distinct advantage in this use of this improved form of suspension nut in that by the manner in which it is locked in position, all looseness of the parts may be taken up and the threads protected from wear. The lower end of nut 19, is faced or beveled at an angle such that it will have a surface bearing on the wearing ring 20 when the shaft is thrown over to the working angle and as it gyrates the lines of contact proceed around this face.

125 The most important feature of the invention relates to the construction at the lower end of the main gyratory shaft 12 and the means by which the gyratory motion is imparted to the shaft and to the crusher head 11. A bearing for the lower end of the shaft is 130

provided in the hub of the spider 25. That portion of shaft 12 entering the lower bearing, like that portion described in the upper bearing, is preferably cylindrical in form and is surrounded by bushing 26 which is so formed together with the bearing that the shaft may partake of its gyratory movement without binding therein.

27^c is a dust cap or collar fitting around the lower end of the shaft adapted to have a sliding movement over the top of the bearing as the shaft moves in relation to the spider. The spider 25 is preferably provided with a plurality of arms with openings between and in fact such construction is essential in order that means may be provided for the discharge of the crushed material through the spider into the discharge hopper and discharge spout below. Heretofore in this class of machines, it has been the common practice to provide discharge means for the crushed material immediately below the crushing head. The main gyratory shaft has then been lengthened to a considerable distance to extend below the discharge means after passing beyond which it has been journaled in means for imparting the desired movement to it. All of this has resulted in an undue lengthening of the main gyratory shaft and consequently a machine of considerable height. To avoid such construction and to produce a machine with a reasonably short gyratory shaft and much less in height than heretofore the practice in this class of machines, is the primary object of the invention.

The arms of spider 25 before referred to radiate outwardly and preferably extend beyond the outside wall of the upper shell or crushing chamber 10, which latter member is mounted on a lower plate or base 27, which is provided with openings through which the arms of the spider extend. The outer extremities of the spider arms are preferably provided with a circumferential rim 25^a which is provided with an upwardly extending flange 25^b around its periphery.

In the embodiment of the invention, shown, it will be apparent that while the weight of the main gyratory shaft 12 and crushing head 11 are suspended from the upper bearing, no provision is made for carrying the weight of the spider 25 from the suspended shaft. Independent means for sustaining the weight of the spider is shown in Fig. 1 consisting of wearing plate 28 mounted in base plate 27, plate 29 similarly mounted in the circumferential rim of the spider and ball bearing cage 30. It will be apparent that any suitable form of bearing adapted to support the spider in its gyratory movement may be employed, which movement is imparted to the spider by means of the rotating eccentric ring 31 interposed between the outer wall of the

upper shell or crushing chamber and the upwardly extending circumferential flange 25^b of the spider. Rotation is preferably imparted to eccentric ring 31 by means of rim-pulley 32, which may be made in halves and bolted together in the usual way to facilitate removal for inspection. The lower outer edge of rim-pulley 32 is provided with a flanged surface 32^a which is carried on suitable supporting rollers 33. This rim-pulley is also provided with an upper bearing surface 32^b adapted to coöperate with suitable rollers 34 for preventing upward movement. 35 is a spindle which may be screw threaded into lower base member 27 or secured thereto in any desired manner for supporting roller 33.

36 is a form of shield for roller 33 which may be formed integral with base member 27, as illustrated.

37 is a flange secured in any desired manner to upper shell or crushing chamber 10 and designed as a protective covering for the eccentric ring 31 and its bearings. This shield may be formed in sections as illustrated in Fig. 2, portions of which, as 37^a, may be hinged to admit of their being raised to permit inspection of the eccentric ring and its bearings, to permit lubrication of these parts and also to permit access to the nuts of bolts 38 which are used in securing the lower plate or base 27 and the crushing chamber 10 together. A portion of shield member 37 may also be formed as a covering and a support for rollers 34 adapted to take the upward thrust of rim-pulley 32 as illustrated at 37^b, Figs. 1 and 2.

In order to furnish a suitable bearing, as well as anti-friction means between eccentric ring 31 and its coöperating parts on crushing chamber 10 and spider 25, a bushing 39 may be provided in flange 25^b and a sleeve 40 furnishes a similar bearing around the lower edge of the crushing chamber. When spider flange 25^b and crushing chamber 10 are made of suitable material for bearings, bushing 39 and sleeve 40 may be omitted as shown in Fig. 4.

While it will be apparent that the desired gyratory movement would be imparted to spider 25 and to shaft 12 by inserting eccentric ring 31 between the bearings described on the crushing chamber and the spider, yet it is preferred to use suitable anti-friction means, as, for example, roller bearings 41 contained in suitable sectional cages 42. The construction of these bearings and their retaining cages are shown in detail in Figs. 10 and 11, from which it will be seen that the cylindrical rollers 41 are journaled between members 42, held in position by suitable retaining members 43. It is common in bearings of this description to construct them in one continuous circumferential member and such construction may be used

here, but it is preferred that these bearings be divided into a number of sections, as illustrated, which makes them much more convenient in assembling or in removing or 5 replacing broken or worn portions. In order to provide against wear due to the centrifugal action of these bearings it is preferred that rollers 44 be provided at the ends of each section, which will reduce the friction 10 of supporting members 42.

Base member 27 is preferably provided around its outer edge with an upwardly extending flange 27^a, near the base of which a groove 27^b is formed. This flange provides 15 a protection for the bearings and the groove furnishes a means for the collection of waste lubricating oil.

As the material introduced into the machine is crushed between head 11 and concaves 23 and falls downwardly, it will pass 20 between the radiating members of spider 25 and portions of it will strike the arms of the spider, which constant action wears these parts greatly. To provide against 25 such wear, shields 45 are secured over the top surfaces of these spider arms. As a further means for preventing material from reaching unprotected parts of the spider arms and for preventing dust from entering 30 the bearings for operating and supporting the spider shields 46 are secured near the lower edge of crushing chamber 10 and to these shields other shields 47, preferably of flexible material as cloth and the like, are 35 secured and are adapted to extend downwardly and close the opening through which the spider arms extend. These flexible shields of course may be made to surround very closely the spider arms and thereby 40 effectually prevent dust and particles of the crushed material from entering the bearings. A suitable hopper or receptacle is secured to the bottom member 27 or such hopper may be formed integral therewith. 45 As illustrated in Figs. 1 and 2 this hopper, indicated by reference character 48, is formed independently of base plate 27 and secured thereto by suitable retaining bolts 49. The spout 48^a is formed integral with 50 the hopper although it will be apparent that it may be formed separately and secured to it in any desired manner. It is found that the constant action of the material coming 55 from the crushing chamber has a wearing effect upon the hopper, which after a time makes it necessary to replace the same. To avoid such wear, the hopper 48 instead of being constructed on a steep incline toward the spout has its exposed surface corrugated 60 in the manner illustrated in the sectional view in Fig. 1, or the incline of the surface may be made very slight which construction causes portions of the material to lodge on the surface thus formed in the 65 hopper in a manner that will be apparent,

so that the crushed material as it drops into the hopper instead of striking the surface of the hopper wears against other material previously deposited.

In Fig. 15 a modified form of hopper is 70 shown, which construction, if followed, permits of still further shortening of the length of the entire machine as it enables the hopper to be constructed in closer proximity to the spider and as it is carried by the spider 75 instead of being secured to the base of the machine, as shown in Figs. 1 and 2, the gyratory movement of the spider is imparted to the hopper, which movement facilitates the passage of the crushed material through the hopper and the discharge spout, thus making it possible to construct the hopper and the spout with a much less incline than when constructed as shown in 80 Figs. 1 and 2. In said modification the 85 hopper is indicated by the reference character 50 and the spout by 50^a. It may be attached to the spider in any desired manner, although specific means for securing the parts together is not illustrated in the drawing, yet it will be apparent that the same bolts, as bolts 51, which are used for securing shields 45 to the arms of the spider, may be employed for securing the hopper thereto. If desired, this hopper may be cast 90 integral with said spider. In this modification the base member 52 need not differ from the form illustrated in Figs. 1 and 2, since the base 27 may readily be used in conjunction with this modified form of 95 hopper.

In Fig. 4 is shown a modified form of means which may be employed in driving the eccentric ring 31, consisting of a circular ring or face gear 53 meshing with bevel pinion 54 on horizontal driving shaft 55. Shaft 55 may be driven by any suitable means, as driving pulley 56. This means of driving may under some conditions be found more convenient in communicating power 105 to the machine and when employed an extension 57 may be formed integral with base plate 27 and the shaft 55, and its bearing 58 secured to this extension in any desired manner.

The concaves or plates 23 which line the interior of the crushing chamber and co-operate with the crushing head are usually made to come level with the crushing chamber at the top and are overlapped by the 120 hopper or by the rim of the spider which supports the main gyratory shaft at its upper end. When thus constructed if the concaves vary in thickness, a ledge may be formed by the thicker ones by which large 125 particles of material entering the crushing chamber lodge and in this manner obstruct the feed. Again these concaves are sometimes made of material that expands until it comes in contact with the spider or hop- 130

per and may cause breakage. As shown in the present construction, particularly in Figs. 1 and 8, these concaves have at their upper extremities extensions 23^a extending beyond the upper edge of the crushing chamber and have their upper surface bevelled or inclined in order to provide a continuation of the inclined surface of the receiving hopper 59, thus securing a practically smoother, inclined surface for feeding the material into the crushing chamber.

Receiving hopper 59 rests upon the top of the crushing chamber and may be formed in a plurality of sections and bolted together as illustrated more particularly in Fig. 9. It is the common practice to make the inclination of feed hoppers in machines of this class the same in all points of its circumference. Since the arms of the spider 20 which support the gyratory shaft at its upper end, rise above the inclined surface of the hopper, material which is being fed into the crushing chamber lodges against the spider arms, which results in obstructing the feed to an extent. The improved manner of constructing the sections of the hopper adjacent the spider arms as illustrated in Figs. 1, 2, 8 and 9 avoids any such obstruction since the surface 59^a of the hopper 25 forms a shed preventing the material from striking the spider arms and it will be apparent that the elevated surfaces 59^a may be formed by separate pieces secured to a hopper of the usual construction. To protect the spider arms against wear from material dropping upon them from above, they are provided with the usual shields 60 and secured to the arms in any desired manner, as by bolts 61.

40 While rim-pulley 32 may be formed integral with eccentric ring 31 or secured thereto in any suitable manner, the form of construction shown in detail in Figs. 1, and 12 to 14, is preferred. In this construction the upper edge of the eccentric ring is formed of uniform thickness throughout and is formed eccentric only on that portion which coöperates with the bearings on the gyratory spider. This upper 45 concentric portion of the ring furnishes the means for securing the concentric rim-pulley thereto. The parts may be secured together by the tap bolts 62, one or more of which may be used in locking keys or 50 pins 63, as illustrated in Figs. 1, 13 and 14, for the purpose of firmly securing the parts together.

In order that the invention might be fully understood by those skilled in the art, the 55 details of the foregoing embodiment thereof have been thus fully described, but

What I claim as new and desire to secure by Letters Patent is—

1. In a machine of the class described in 60 combination, a crushing chamber, a crush-

ing head, a gyratory shaft, a spider adapted to furnish suspension means for said shaft adjacent the upper extremity thereof and adapted to permit a gyratory movement of the shaft, a spider into which the lower end 70 of the shaft is journaled, the said spider being provided with members extending beyond the walls of the chamber, and means adapted to impart a gyratory movement to the last said spider in relation to the crushing chamber, said means comprising an eccentric ring interposed between the said spider and the crushing chamber.

2. In a machine of the class described in combination, a main crushing chamber, a 80 stationary spider carried by the said chamber at its upper extremity, a main gyratory shaft provided with a crushing head journaled in said spider and suspended therefrom to permit a gyratory movement of said 85 shaft in relation to the spider and the crushing chamber, a spider at the lower extremity of the gyratory shaft and connected therewith, said spider being mounted on suitable bearings whereby it is susceptible 90 of a gyratory movement and having portions thereof extending beyond the outer walls of the crushing chamber, an eccentric ring interposed between the said outer portions of the spider and the chamber, and driving 95 means for imparting a rotary movement to said eccentric ring whereby the said spider and the gyratory shaft are caused to gyrate in relation to the crushing chamber.

3. In a machine of the class described in combination, a crushing chamber, a main gyratory shaft, a stationary spider fixed to the crushing chamber, a suspension bearing in said spider adapted to carry the upper 100 end of the gyratory shaft, a spider at the lower extremity of the shaft and connected therewith, arms on said spider extending beyond the outer walls of the chamber through openings in the walls of the chamber, and means on the exterior of the chamber for imparting a gyratory movement to the spider, said means comprising an upwardly extending flange around the periphery of the spider, and an eccentric ring mounted to rotate between said flange and 110 a suitable bearing surface fixed in relation to the crushing chamber.

4. In a machine of the class described in combination, a crushing chamber, a spider fixed to said chamber, a main gyratory shaft 120 suspended from said spider, a non-rotating spider in which the lower end of said gyratory shaft is journaled, a bearing for permitting gyratory movement of the last said spider in relation to the main crushing chamber, and means for imparting a gyratory movement between said last mentioned spider and the crushing chamber, said means comprising an eccentric ring interposed between the spider and a suitable 125

130

bearing surface in fixed relation to the chamber, and means for imparting movement to said eccentric ring.

5. In a machine of the class described in combination, a crushing chamber, a spider fixed to said chamber, a main gyratory shaft suspended from said spider, a second spider into which the lower end of said gyratory shaft is journaled, a bearing for permitting movement of said spider in relation to the main crushing chamber, means for imparting relative movement between said last mentioned spider and the crushing chamber, said means comprising an eccentric ring interposed between the spider and a suitable bearing surface in fixed relation to the chamber, and means for imparting movement to said eccentric ring comprising a concentric rim-pulley secured thereto.
10. In a machine of the class described in combination, a crushing chamber, a main gyratory shaft having one end thereof journaled in fixed relation to said chamber but adapted to have a gyratory movement in such fixed bearing, a movable spider into which the other end of said shaft is journaled, means for imparting a gyratory movement to the last said spider, a bearing adapted to carry the weight of the movable spider, said bearing comprising plates secured to the spider and to a member fixed to the crushing chamber, and a ball bearing cage between said plates and a flexible shield coöperating with the wall of the chamber and the spider whereby the dust from the crushing chamber may be excluded from the bearing.
15. In a machine of the class described in combination, a crushing chamber, a main gyratory shaft on the interior of the chamber, a spider movably mounted in relation to the chamber for imparting gyratory movement to the shaft, a flange on the periphery of the spider extending around the outer wall of the chamber, an eccentric ring interposed between the flange and the outer wall of the chamber, and anti-friction means adapted to take the thrust between said eccentric ring, said flange and the wall 20 of the chamber comprising a plurality of roller bearings.
20. In a machine of the class described in combination, a crushing chamber, a main gyratory shaft, a spider secured to the gyrating end of said shaft and having a portion thereof extending around the outer walls of the chamber, an eccentric ring interposed between the spider and a suitable bearing surface in fixed relation to the chamber, a 25 rim-pulley secured to said eccentric ring and anti-friction means for supporting said rim-pulley comprising bearing surfaces adapted to support said rim-pulley against both upward and downward movement, and

30 mounted in fixed relation to the crushing chamber and coöperating with said bearing surfaces on the rim-pulley.

35. In a machine of the class described in combination, a crushing chamber, a base supporting said chamber and forming a continuation of the walls thereof, a main gyratory shaft suspended above the upper extremity of the crushing chamber by a bearing in fixed relation to said chamber but adapted to permit a gyratory movement of the lower end of said shaft, a movable spider connected with the lower end of said shaft and having the arms thereof extending outwardly through openings formed in the walls formed by the chamber and its base, said spider being formed with open spaces between the arms thereof through which material from the crushing chamber may pass, means for imparting a 40 gyratory movement to said spider, and a discharge hopper and spout below the said spider.
40. In a machine of the class described in combination, a crushing chamber, a main gyratory shaft suspended from the upper end of said chamber, means for imparting a gyratory movement to the lower end of said shaft comprising a spider having a plurality of radiating arms extending beyond the outer walls of the chamber, a base plate adapted to support the said crushing chamber and to form a continuation of the walls thereof, there being openings formed in the walls of the chamber and the plate through 45 which the radiating arms of the said spider pass, means on the exterior of the walls formed by the chamber and the base for imparting gyratory movement to the spider, and an upwardly extending flange around the outer periphery of the base whereby protective means for the mechanism operating the spider is secured.

50. In a machine of the class described in combination, a main crushing chamber, a main gyratory shaft, a spider connected with the lower end of said shaft, means for imparting a gyratory movement to said spider, a base adapted to support said crushing chamber, the walls thereof being adapted to form a continuation of the walls of the crushing chamber, a bearing surface formed on the said base adapted to support the said movable spider, an upwardly extending flange around the periphery of the base adapted to furnish a shield to the said spider bearing, and a groove around the periphery of the base adjacent the said flange adapted to furnish a receptacle for waste lubricants.
55. In a machine of the class described in combination, a crushing chamber, a crushing head, a main gyratory shaft carrying said crushing head, a spider in fixed relation to said chamber adjacent the upper side thereof and extending beyond the upper ex-

60. In a machine of the class described in combination, a crushing chamber, a main gyratory shaft, a spider connected with the lower end of said shaft, means for imparting a gyratory movement to said spider, a base adapted to support said crushing chamber, the walls thereof being adapted to form a continuation of the walls of the crushing chamber, a bearing surface formed on the said base adapted to support the said movable spider, an upwardly extending flange around the periphery of the base adapted to furnish a shield to the said spider bearing, and a groove around the periphery of the base adjacent the said flange adapted to furnish a receptacle for waste lubricants.
65. In a machine of the class described in combination, a crushing chamber, a crushing head, a main gyratory shaft carrying said crushing head, a spider in fixed relation to said chamber adjacent the upper side thereof and extending beyond the upper ex-

tremities of the walls of the chamber, and a receiving hopper at the upper extremities of the walls of the chamber and being provided with elevated portions in its upper 5 surface opposite the arms of the spider whereby material fed into the hopper is deflected and passes into the chamber without striking the spider arms.

13. In a machine of the class described in combination, a crushing chamber, a crushing head, a main gyratory shaft supporting said crushing head, a spider secured to the walls of the crushing chamber adjacent the upper extremities thereof adapted to furnish 10 a bearing for the main gyrating shaft, and a hopper at the upper extremities of the walls of the chamber, said hopper comprising a plurality of sections, and the upper surfaces of said sections adjacent the spider 15 arms being formed to shed incoming material into the chamber without contacting with the spider arms.

14. In a machine of the class described in combination, a main gyratory shaft, a crushing chamber, a spider carried by the crushing chamber and adapted to furnish sus- 20

pension means for said shaft, a bearing or seat on said spider adapted to coöperate with an enlargement or collar on said shaft, and an adjustable collar on said shaft comprising 30 a sleeve provided with a threaded inner portion adapted to correspond with a similar threaded portion on the shaft and being provided with a thickened lower bearing surface adapted to coöperate with the seat 35 or bearing on the spider, there being longitudinal slots through the walls of the sleeve intersecting the threads, a collar adapted to be inserted over the slotted and threaded portion of said sleeve, there being tapered surfaces whereby the forcing of the collar over the sleeve locks the same in position on the shaft, and means for locking the said collar and the sleeve together.

In testimony whereof I have signed my 45 name to this specification, in the presence of two subscribing witnesses, on this eighth day of February, A. D. 1908.

JACOB M. SHOLL.

Witnesses:

FRANK WAIT,
J. C. BULLOCK.
